S. W. Gibbs, of Albany, N. Y.

Des. 907

Assignor to

Rathbone & Co, of the same place.

Letters Patent No. 907. Dated July 7, 1857.

The schedule referred to in this Letters Patent, and making part of the same.

Be it known that I, Samuel W. Gibbs, of the City of Albany, State of New York, have produced a new and original ^{ornamental} design, for the plates of a Cooking Stove, (which stove is called the United States,) and I declare that the annexed delineations forming part of this specification, are full and accurate representations of the said plates, which are combined to form in part . . . the said stove, with their ornamental parts; the back and front oven plates; the oven doors, and the front doors of the stove, being symmetrically similar to each other.

What I claim as my production and desire to secure by Letters Patent, is the combination and arrangement of Ornamental figures and forms, represented in the accompanying drawings forming together the ornamental design for the plates of a Cooking Stove.
